(57) **CLAIM**

The ornamental design for a webcam cover, as shown and described.

DESCRIPTION

FIG. 1 is a front perspective view of a webcam cover in a closed position to cover a webcam of an electronic device; FIG. 2 is a front perspective view of the webcam cover of FIG. 1 in an open position;

FIG. 3 is a front elevational view thereof;

FIG. 4 is a top plan view thereof;

FIG. 5 is a bottom plan view thereof;

FIG. 6 is a left elevational view;

FIG. 7 is a right elevational view thereof; and,

FIG. 8 is a rear perspective view thereof showing a magnetic that can be used to attach the webcam cover to an electronic device.

The broken lines shown in the drawings are included to illustrate environmental subject matter and form no part of the claimed design.

1 Claim, 4 Drawing Sheets
